UNITED STATES PATENT OFFICE.

WILLIAM RALPH HURSEY, OF ASHEVILLE, NORTH CAROLINA, ASSIGNOR OF ONE-FOURTH TO BASIL H. OATES, OF TUSCALOOSA, ALABAMA.

FLUSH-TANK.

1,381,465.

Specification of Letters Patent. Patented June 14, 1921.

Application filed September 24, 1919. Serial No. 326,017.

To all whom it may concern:

Be it known that I, WILLIAM R. HURSEY, a citizen of the United States, residing at Asheville, in the county of Buncombe and 5 State of North Carolina, have invented certain new and useful Improvements in Flush-Tanks, of which the following is a specification.

This invention relates to flush tank apparatus and more particularly to apparatus of the general type disclosed in my prior Patent 1,314,873, dated September 2nd, 1919.

The general objects of the present invention are substantially the same as those stated in the above mentioned patent, namely the provision of means for locking the outlet valve in its raised or open position during the descent of the float and for releasing such valve and causing it to close 20 when the float reaches its lowest position. The invention also eliminates the usual hollow rubber ball employed as an outlet valve, and in its place utilizes a disk valve which is heavier than water.

25 More specifically the present invention seeks to provide improved details of construction not present in my former design. Among such details are an improved inlet and outlet valve and a simplified arrangement of interlocking parts whereby these 30 two valves are opened and closed at the proper time by means of a float lever.

In order that the invention may be readily understood, reference is had to the accompanying drawings forming part of this application, and in which:

Figure 1 is a sectional view of a flush box or tank equipped with my improved valve mechanism, parts being in elevation and 40 showing the tank full;

Fig. 2 is a similar view on an enlarged scale, parts being broken away, and showing the outlet valve open and locked;

Fig. 3 is a view similar to Fig. 2 but showing the outlet valve closed and the float lever in its lowermost position;

Fig. 4 is a plan view of the parts shown in Fig. 3, a portion of the outlet valve being broken away;

50 Fig. 5 is a transverse section on the line 5-5 of Fig. 3 looking in the direction of the arrow;

Fig. 6 is a transverse section on the line 6-6 of Fig. 3 looking in the direction of the 55 arrow; and

Fig. 7 is an elevation of the improved guide member forming part of my present invention.

Referring to the drawings in detail, 1 designates the usual tank or flush box which 60 may be of any desired construction. 2 designates the threaded stem or nipple of the inlet valve seat, and 3 the threaded nipple of the outlet valve seat.

The usual overflow pipe is indicated at 65 4, and into this extends the upper end of a re-fill tube 5, which is generally employed.

6 designates any suitable float. This is carried by a lever 7 adjustably connected by means of slot 8 and bolt 9 with an arm 10 70 forming an extension of a lever 11 pivoted at 12 between two fixed arms 13 rigidly carried by the inlet valve casing or body 15.

Referring to Fig. 5 it will be seen that this valve casing is provided with a discharge opening 16 at one side thereof, through which water flows into the box. The re-fill tube 5 also extends into this casing. 17 designates a central bore or opening extending through the valve body and 80 terminating at its upper end in a valve seat 18 having a thin upper edge. This valve seat is disposed concentrically of the casing 15. The parts 5, 16 and 17 are so proportioned that sufficient water can flow through 85 17 to supply both 5 and 16. In other words, the water flows into the body 15 of the valve at a rate high enough to create sufficient pressure to lift it through the refill tube 5, notwithstanding the restricted opening 16. 90

The chamber within the valve body is closed at the top by means of a reciprocating disk valve 20 having a flange 21 which fits snugly within the chamber of the valve body. The valve 20 has a central recess 95 within which is mounted a cushion 19 of rubber, leather, or the like, adapted to engage the valve seat 18 when the valve 20 is lowered.

At the top of the valve 20 are a pair of 100 guide lugs 22, between which freely works a valve operating lever 23, pivoted at 25 to a bracket 26 carried by the valve body 15.

At the forward end of the lever 23 is formed a concave notch or seat 24 in which 105 is received a pin 14 carried by the lever 11 above mentioned. It will thus be seen that when the float lever 7 is in its raised position as shown in Figs. 1 and 2, the pin 14 bears down upon the end of lever 23 thus 110

forcing the valve 20 and disk 19 firmly against the seat 18, thereby shutting off the flow of water into the box. When, however, the float lever 7 is lowered, the lever 23 is released and the water pressure forces the valve 20 upwardly, thus permitting water to flow into the tank.

The outlet valve body is provided with an annular flange 27 by which it is supported 10 on the tank bottom, and terminates at its upper end in a thin edged valve seat 28. The overflow pipe 4 is set into a branch 4^a of the outlet valve body and communicates with the interior thereof through a port 4^b.
 15 Adapted to coöperate with the valve seat 28 is an outlet valve designated in its entirety by the reference numeral 29. This valve comprises a flat, circular casing 30 having ports 31 therethrough to prevent possible trapping of water therein. The lower edge of the casing 30 is provided with a series of inwardly projecting lugs 32. Within the casing are disposed a metal disk 33 and a disk 34 of rubber, leather, or other suitable material, the metal disk having lugs 35 adapted to coöperate with the lugs 32 to retain the disk in position. As will be obvious, the lugs 35 are capable of passing through the spaces between the lugs 32, and then, when given a partial turn, the disk will be retained behind the lugs 32.

The casing 30 is provided at its center with an inwardly projecting bump or protuberance 36 having a conyex surface adapted to bear upon the center of the metal disk 33. It will be obvious that this arrangement permits the metal disk 33 to partake of slight angular movement relative to the casing 30 and thus cause the disk 34 to lie 40 snugly against the seat 28, thus compensating for any inaccuracies of size or adjustment in the valve levers and associated parts.

The casing 30 is provided with a hollow 45 boss 37 into which is secured one end of a lever 38. This lever is adjustably secured at its other end by means of a set screw in a socket carried by a catch 39, pivoted at 12 to the fixed bracket 13. This catch 39 is preferably provided near its upper edge with a laterally projecting lug 40, this serving to increase the width of the catch.

A relatively heavy gravity latch 41 is pivoted at 25 in substantially the same plane as the lever 23 and is provided at its free end with a notch or hook 42 adapted to engage the lug 40 carried by the catch 39. Fig. 2 shows these parts in engagement.

The latch 41 is adapted to be released 60 from the lug 40 and catch 39 by means of the pin 14 carried by the float lever. This pin is arranged to engage under a central fin or lug 43 projecting from the lower side of the latch 41 and thereby lift said latch. The 65 forward side of lug or fin 43 is recessed to

receive lug 40 and the parts are so proportioned that engagement of the lug with the fin serves as a stop to limit the upward movement of the valve lever.

The outlet valve casing 30 is provided 70 with a hook or eye 45 to which is attached a lifting chain 46, the other end of said chain being secured to a manual operating lever 47 which may be actuated in any suitable way. 75

In order to prevent any possibility of the valve casing 30 and associated parts becoming displaced laterally relative to the seat 28, I preferably provide a guide bracket adapted to engage the valve stem or lever 80 38. This bracket preferably consists of a sheet metal ring or washer 48 adapted to be clamped between the flange 27 and the bottom of the tank. This washer 48 carries an upstanding arm 49, the upper end of which 85 is bifurcated to form a pair of guide members 50 having between them a slot in which the valve lever 38 works. It will be noted that the guide bracket 49 is angularly adjustable relative to the outlet valve body and 90 associated parts, such angular adjustment being readily accomplished by shifting the ring 48 around the valve body to any desired location before it is clamped in position, as by means of a lock-nut 3^a. This angular 95 adjustment is important from a practical standpoint for the reason that inlet and outlet openings are disposed in different relations in different makes of tanks. By having the bracket adjustable it becomes possible to properly assemble the parts of my improved valve mechanism whatever may be the location of the inlet opening relative to the outlet. 100

The operation of the apparatus as a whole 105 will now be briefly described. With the tank full and the float in its elevated position as shown in Fig. 1, the inlet valve will be held closed by the pressure of the pin 14 on the end of lever 23. When it is desired to flush 110 the tank the lever 47 is operated, thus lifting the valve casing 30 and associated parts from the seat 28 and permitting the water to escape through the outlet 3. The lifting of the valve casing 30 rotates the latch 39 clockwise about its pivot 12 until the hook 42 of the latch 41 drops by gravity over and engages the lug 40 as clearly shown in Fig. 2, thus locking the outlet valve in its raised or open position. The parts remain 115 in this position while the water is running out and the float gradually falling. When the float finally reaches its lower position, as indicated in Fig. 3, the pin 14 carried by the float lever engages under the fin or lug 43 and thus lifts the latch 41 out of engagement with the lug 40. This permits the 120 valve casing 30 and associated parts to fall by gravity from the dotted line position in Fig. 3 to the full line position, thus closing 125 130

the outlet. At the same time the pin 14 has been moved away from lever 23, thus permitting the inlet valve to be forced open by water pressure, and allowing the tank to fill.

It will thus be seen that I have provided a very simple arrangement in which the float lever serves to actuate the inlet valve and also to control the gravity latch which locks the outlet valve in raised position during the time that the water is running out of the tank. It will also be seen that I have provided both inlet and outlet valves of improved construction, and it is thought that the many advantages of my invention will be appreciated by those skilled in the art without further discussion.

What I claim is:—

1. In a flush tank apparatus, a float operated lever and outlet valve lever independently mounted about a common pivot, a hook arranged to engage and hold the valve lever while permitting free movement of the float lever, and means carried by the float lever for shifting said hook out of engagement with the valve lever.

2. In a flush tank apparatus, an inlet valve lever, an outlet valve lever, a latch controlling the latter, and a float lever having a part adapted to engage either said inlet valve lever or latch.

3. In a flush tank apparatus, an inlet valve lever, an outlet valve lever, a latch controlling the latter, and a float lever having a part disposed between said inlet valve lever and latch, and adapted to engage them alternately as the tank is operated.

4. In a flush tank apparatus, an inlet valve lever, an outlet valve lever, a latch controlling the latter, and a float lever having a laterally projecting pin disposed between said inlet valve lever and latch, and adapted to engage one or the other of said parts.

5. In a flush tank apparatus, an inlet valve lever, an outlet valve lever, a latch controlling the latter, and a float lever pivoted alongside of said outlet valve lever, and having a laterally projecting pin disposed between said inlet valve lever and latch.

6. In a flush tank apparatus, an inlet valve lever and a latch pivoted about a common center, an outlet valve lever having a catch adapted to be engaged by said latch, and a float lever having a projection arranged to engage said inlet valve lever when the float lever is in one position, and to engage and trip said latch when the float lever reaches another position.

7. In a flush tank apparatus, an inlet valve lever and a latch pivoted about a common center, an outlet valve lever having a catch adapted to be engaged by said latch, a float lever, and means actuated by the movement thereof for operating both said latch and inlet valve lever.

8. In a flush tank apparatus, a pivoted outlet valve lever, a lug carried thereby, a pivoted latch adapted to engage said lever and lock said valve when moved to open position, and means arranged to engage said lug to limit the opening movement of said valve.

9. In a flush tank apparatus, a pivoted outlet valve lever, a lug carried thereby, a pivoted latch adapted to engage said lever and lock said valve when moved to open position, and means carried by said latch for engaging said lug to limit the opening movement of said valve.

10. In a flush tank apparatus, an outlet valve comprising a valve seat, and a valve member coöperating therewith, said valve member comprising a relatively thin flat casing, and superposed disks of rigid and flexible material loosely mounted in said casing, and capable of movement relative thereto, said flexible material being arranged to engage said valve seat.

11. In a flush tank apparatus, an outlet valve comprising a valve seat, and a valve member coöperating therewith, said valve member comprising a relatively thin flat casing, and superposed disks of rigid and flexible material loosely mounted in said casing, the center of said casing being provided with an internal projection about which said disks may freely pivot, so as to cause the flexible disk to lie flat against said seat.

12. In a flush tank apparatus, the combination with an outlet valve comprising a seat and a valve member carried by a lever pivoted at a point located to one side of said seat, of a guide bracket coöperating with said lever, said guide bracket being mounted adjacent the seat, and angularly adjustable therearound.

13. In a flush tank apparatus having an outlet pipe, and pivoted outlet valve and lever coöperating therewith, a guide bracket comprising a ring adapted to surround the outlet pipe, and provided with a bifurcated upstanding portion adapted to receive the outlet valve lever.

In testimony whereof I affix my signature.

WILLIAM RALPH HURSEY.
